(57) **CLAIM**

The ornamental design for pneumatic tyre, as shown and described.

DESCRIPTION

FIG. 1 is a front view of pneumatic tyre showing our new design;

FIG. 2 is a back view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines shown in the drawings depict portions of the pneumatic tyre that form no part of the claimed design.
